UNITED STATES PATENT OFFICE.

SEYMOUR W. PEREGRINE, OF GRAND RAPIDS, MICHIGAN.

WOOD-WORKING MACHINE.

SPECIFICATION forming part of Letters Patent No. 416,492, dated December 3, 1889.

Application filed May 31, 1889. Serial No. 312,714. (No model.)

To all whom it may concern:

Be it known that I, SEYMOUR W. PEREGRINE, of Grand Rapids, in the county of Kent and State of Michigan, have invented a new and 5 useful Improvement in Wood-Working Machines; and I do hereby declare that the following is a full, clear, and exact description of the same.

In the manufacture of school-seats in which 10 slats are used recesses are formed on the rear side of the slats to receive lugs on the standard, by which they are supported and held in place. Each slat has a recess, preferably dovetailed to correspond with the lug, and these 15 several recesses open into each other, thus forming a continuous groove or recess extending across the seat or back.

My invention is a machine for forming these recesses.

20 In the drawings, Figure 1 is a perspective view of the table, the seat in place, and the cutter and means for operating it. Fig. 2 is a sectional view through the table and frame, some of the parts being in side elevation. 25 Fig. 3 is a detail of the cutting-tool and its supporting-block.

In the drawings, A is the frame, rectangular in form and supported by legs B, and may be of channel-iron, as in Fig. 2. Within the frame 30 is a movable table C, which receives the work to be operated upon, and, as in the present case, rests c may be used on the table corresponding in shape to the seat or back for supporting the same firmly.

35 Above the table at each end are clamping-plates D D', extending from side to side of the frame and secured thereto. These plates conform in shape to the seat or back, and on their under sides may have additional plates F, 40 made removable, so that backs of different curves may be operated on. The seat or back after being placed on the table is held in order to be operated upon by the upward movement of the table, which clamps said seat between itself and the plates. The table rests 45 upon bell-crank levers E, pivoted to the frame, the ends of said levers engaging adjustable inclines on the under face of the table. The lever-arms a are connected to a treadle G by

50 rods 1 2, and the treadle is held normally up by a pulley-spring I, and when it is in this position the levers are as shown in dotted lines

and the table is in its lowest position, ready to receive the work, it being supported by the upper ends of the bell-crank levers and the 55 pins 3 3, resting on the horizontal arms a. The movement of the levers is limited by projections x. By depressing the treadle the table is forced up and the work clamped. A pivoted stop-arm N holds the treadle down.

60

The plates D D', besides forming a portion of the clamping and holding means, also act to control and guide the cutting-tool, for which purpose they have openings extending longitudinally, the contour of which corresponds to 65 the shape of the recess to be cut, the shape shown being a series of connected dovetails. The cutting-tool passes through this plate and removes the material directly beneath the opening, its lateral movement of course being 70 controlled by the edges of the plate about the opening.

The tool 4 is on a shaft 5, journaled in the head 6, at the lower end of which is a ball 7, adapted to a socket in the block D². The 75 block has flanges embracing the edges about the opening in the plate, so that the said block may slide along said plate to bring the cutter into action at different points to form the recess. The block is formed as in Fig. 3 to allow lateral movement. The front end of the 80 plate is open to allow the admission and withdrawal of the block and cutter at will. The ball-and-socket joint allows the shaft to remain vertical without regard to the inclination of the work and the block D². The shaft is driven by belts 8 9 through pulleys 10 11 12 on a jointed frame composed of bars y z, the latter of which is journaled on a shaft w, which is rotated by a belt 14 and pulley 15. There 85 is a plate D and D' at each end of the table, and when the recess has been formed in one end of the seat or back the block D², with the cutter, is slid out of the plate and the jointed frame is moved, so that it may be inserted in 90 the other plate to cut the recess there.

95 I claim—

1. In combination, the supporting-frame, a vertically-movable table for holding the work, a clamping-plate extending over said table and secured permanently to the supporting-frame, said rigid clamp-plate having an opening for the cutting-tool and constituting the pattern, substantially as described.

2. In combination, the rectangular supporting-frame A, the table vertically movable within said frame, a clamping and guiding plate extending above and across the movable table and secured permanently to the rectangular frame, substantially as described.
5. In combination, the cutters, the clamping-plate, the movable table, the frame, the 20 levers for supporting and operating said table, the treadle, the spring, and the holding means, substantially as described.
3. In combination, the supporting - frame, the clamp and guiding plate, the vertically-25 movable table, the bell-crank levers beneath the same, and the inclines arranged to be engaged by said levers, substantially as described.
10. In combination, the supporting - frame, the clamp-plate secured thereto having an opening to guide the cutter, the vertically-25 movable table, and the removable plates F, secured to the under side of the clamp-plates, substantially as described.
15. In combination, the cutters, the clamping-plate, the movable table, the frame, the 20 levers for supporting and operating said table, the treadle, the spring, and the holding means, substantially as described.
6. In combination, the table, the guide-plate, the sliding block on said plate, the cutter-head, having the ball-bearing, and the shaft and cutter, substantially as described.

In testimony whereof I have signed my name to this specification in the presence of two subscribing witnesses.

SEYMOUR W. PEREGRINE.
